CLAIM

I claim the ornamental design for a game board, substantially as shown and described.

DESCRIPTION

FIG. 1 is a perspective view of a game board showing my new design;

FIG. 2 is a front elevational view thereof, the rear elevational view being a mirror image thereof;

FIG. 3 is a sectional view thereof, taken along line 3-3 of FIG. 5;

FIG. 4 is a left side elevational view thereof, the right side elevational view being a mirror image thereof;

FIG. 5 is a top plan view thereof;

FIG. 6 is a perspective view of a second embodiment of a game board;

FIG. 7 is a front elevational view FIG. 6; the rear elevational view being a mirror image thereof;

FIG. 8 is a sectional view thereof, taken along line 8-8 of FIG. 10;

FIG. 9 is a left side elevational view of FIG. 6, the right side elevational view being a mirror image thereof; and,

FIG. 10 is a top plan view FIG. 6.
